CLAIM

We claim the ornamental design for a golf putter with slotted head, as shown and described.

DESCRIPTION

FIG. 1 is a side view of the golf putter with slotted head

FIG. 2 is a top view of the golf putter with slotted head

FIG. 3 is a side view of the golf putter with slotted head from the hitting surface

FIG. 4 is a bottom view of the golf putter with slotted head

FIG. 5 is an end view of the golf putter with slotted head from the toe of the putter; and,

FIG. 6 is an end view of the golf putter with slotted head from the heel.

The golf putter with slotted head is as shown with a longitudinal slot running through the club head.
